UNITED STATES PATENT OFFICE

CHARLES A. HETHERINGTON, OF DES MOINES, IOWA.

ELECTRICAL TESTING DEVICE.

988,192.

Specification of Letters Patent. Patented Mar. 28, 1911.

Application filed December 20, 1909. Serial No. 534,196.

To all whom it may concern:

Be it known that I, CHARLES A. HETHERINGTON, a citizen of the United States, residing at Des Moines, in the county of Polk and State of Iowa, have invented a certain new and useful Electrical Testing Device, of which the following is a specification.

The object of my invention is to provide a screw driver having contained in the handle thereof an electrical testing device whereby the operator may apply the device to two adjacent electric terminals for the purpose of determining whether or not the said wires are electrically charged, and further to provide a device of this kind that is adapted to be used for testing currents of materially different voltage by the use of some incandescent lamp without injury to the lamp such as would be caused by the use of a current of high voltage on the lamp adapted to be lighted by a current of comparatively low voltage; and further to provide a screw driver of this kind in which the blade may be readily and easily detached and another one substituted therefor while maintaining a good electric contact between the blade and the resistance coils.

My invention consists in the construction, arrangement and combination of the various parts of the device whereby the objects contemplated are attained, as hereinafter more fully set forth, pointed out in my claims, and illustrated in the accompanying drawings, in which—

Figure 1 shows a longitudinal, central, sectional view of a device embodying my invention. Fig. 2 shows a transverse, sectional view of same on the line 2—2 of Fig. 1. Fig. 3 shows a sectional view on the line 3—3 of Fig. 1, and Fig. 4 shows a sectional view on the line 4—4 of Fig. 1.

Referring to the accompanying drawings, I have used the reference numeral 10 to indicate the body of the screw driver handle which is made of insulating material and which is formed with a central recess 11. At the rear end of the handle 10 is a screw cap 12 which may be made of metal and which is provided with a glass 13 through which the incandescent lamp on the interior of the screw cap 12 may be seen. At the rear of the recess 11 in the handle is a hinged insulated door 14 that may be held in closed position by a hook 15 and which is provided at its central portion with a socket 16 in which an incandescent lamp 17 is placed.

Contained within the recess 11 of the handle is a metal rod 18 having an insulator spool 19 thereon. Connected with one end of the rod 18 is a conductor 20 electrically connected with the lamp 17 and wound upon the said insulator spool is a resistance coil 21 having one end electrically connected with the lamp socket by means of the conductor 22. This coil has attached to it three terminals; the first one indicated by the numeral 23 being at the end farthest from the left; the second one 24 being about the center of the coil and the third, 25 being connected direct to the conductor 22. Connected with each of these terminals 23, 24 and 25 is a contact head 26 on the side of the handle where it is readily accessible.

The screw driver blade comprises a body portion 27 having a squared end 28 inserted in a suitable opening in one end of the handle. In the squared end of said screw driver blade is a short rod 29 yieldingly held in a direction away from the body of the blade by the spring 30, said rod being in direct alinement with the rod 18 and being held in contact with said rod by the spring 30. For locking the screw driver within the handle, I have provided a locking pin 31 having a notch 32 designed to receive one corner of the squared end of the screw driver blade. In one corner of the screw driver blade is a notch as illustrated in Fig. 1 to receive the pin 31 and said pin 31 is normally held outwardly so that the notch 32 will be away from the corner of the screw driver blade by means of the spring 33. I have also provided for limiting the outward movement of the pin 31 by means of a small pin 34 seated in the handle and inserted in a slot 35 in the pin 31.

In practice if it is desired to remove the screw driver blade the operator first presses the pin 31 inwardly until its notch 32 is in line with the corner of the screw driver, whereupon the screw driver blade may be removed.

In Fig. 1 of the drawings, I have illustrated an object 36 having two electric terminals 37 and 38 thereon. In practical use and assuming that the operator is working with an electric circuit of, say for instance, two hundred and twenty volts, and assuming that he desires to test two adjacent terminals to determine whether or not the wires are electrically charged he then places the one terminal 38 in contact with the terminal

wire 23 of the resistance coil and he places the blade of the screw driver in contact with the other terminal 37. If said wires are charged the current will pass through the 5 resistance coil, through the lamp, then through the rod 18 and the rod 29 to the screw driver blade and return to the other terminal 37. The amount of resistance in the coil from the terminal wire 23 to the 10 lamp is so arranged that a current will be reduced sufficiently to simply cause the lamp to burn in a normal manner. If, for instance, the current with which the operator is working is of one hundred and ten volts, 15 then the terminal 38 is applied to the terminal wire 24 and the resistance between the terminal wire 24 and the lamp is so arranged that the current will cause the lamp to burn in a normal manner. If, for instance, the current with which the operator is working is of comparatively low voltage such, for instance, as is usually found in an 20 electric bell circuit, then the operator places the terminal 38 in contact with the terminal wire 25 and then the current goes direct to the lamp without going through the resistance wire. By this arrangement it is obvious that a single lamp adapted for use with low voltage may be used for indicating 25 to the operator the presence or absence of a current in the wires with which he is working. Furthermore by having the screw driver blade arranged to form one of the terminals for the testing instrument it is 30 obvious that the operator may readily and easily test the current of two wires adjacent to each other or two terminals that are spaced apart at different distances. Furthermore by applying a device of this kind 35 to a screw driver which is an instrument that must be used by electric operators quite frequently the operator will always have at hand a testing instrument, and furthermore by carrying a number of blades 27 of different sizes they may be readily and easily 40 substituted so that the operator need only carry one handle and testing instrument for use in connection with any ordinary work in which he may be employed.

45 Access may be had to the lamp readily and easily by simply unscrewing the screw cap 12, and access may be had to the coil by swinging the hinged door 14 to an open position.

50 I claim as my invention:

55 1. In a device of the class described, the combination of a screw driver handle formed of insulating material and having a recess

on its interior, a screw driver blade connected therewith, a resistance coil contained 60 within the handle, a series of terminal wires connected with the coil at points spaced apart, an electric lamp contained within the handle, and means for electrically connecting the lamp at one side with the coil and 65 at its other side with the screw driver blade, and means for detachably securing the screw driver blade to the handle.

2. In a device of the class described, the combination of a screw driver handle made 70 of insulating material and having a recess therein, a metal rod in the screw driver handle contained in said recess, a screw driver blade inserted in the handle, a spring 75 pressed rod in the screw driver blade designed to engage the rod in the handle, means for locking the screw driver blade in position within the handle, a resistance coil wound upon the rod within the recess, a number of terminal wires connected to said 80 resistance coil at points spaced apart from each other, an electric lamp contained within the handle, means for connecting the resistance coil within one side of the lamp, and means for connecting the other side of 85 the lamp with the rod within said recess.

3. A device of the class described, comprising a screw driver handle made of insulating material and having a recess therein, and also being open at its end, a hinged door made of insulating material to cover said opening, an electric lamp socket in said door, an electric lamp in said socket, a screw cap on the end of the handle to cover said lamp, said cap having an opening therein 95 through which the lamp may be seen, a rod arranged in said recess, an insulator on said rod, a resistance coil wound upon the insulator, means for electrically connecting the resistance coil at one end with the lamp 100 socket, means for electrically connecting the rod with the lamp, a series of terminal wires connected to the resistance coil, the terminal plates arranged in the side of the handle in contact with said terminal wires, a detachable screw driver blade in the handle, means for locking it in position, a spring pressed rod within the screw driver blade, said rod being designed to be held in engagement 105 with the rod on which the coil is supported, substantially as set forth.

Des Moines, Iowa, Dec. 6, 1909.

CHARLES A. HETHERINGTON.
